 2 SHEETS—SHEET 2.

UNITED STATES PATENT OFFICE.

ERNEST L. DE LONG, OF PLANT CITY, FLORIDA.

ELECTROMAGNETIC SHUTTLE-OPERATING MECHANISM.

1,086,444.

Specification of Letters Patent.

Patented Feb. 10, 1914.

Application filed March 18, 1913. Serial No. 755,172.

To all whom it may concern:

Be it known that I, ERNEST L. DE LONG, a citizen of the United States, residing at Plant City, in the county of Hillsboro and State of Florida, have invented certain new and useful Improvements in Electromagnetic Shuttle-Operating Mechanism, of which the following is a specification.

My invention relates to certain new and useful improvements in the means for actuating the shuttles of looms, and one object of my invention is to provide a simple, cheap and highly efficient mechanism by which the usual picker-sticks and their many coacting parts may be entirely dispensed with.

A further object of my invention is to provide electro-magnetic means for throwing the shuttle across the loom and also to provide means for controlling and properly timing the operation of the electromagnetic means.

With the foregoing and other objects in view my invention consists in certain constructions, combinations and arrangements of parts the preferred form of which will be first described in connection with the accompanying drawings and then the invention particularly pointed out in the appended claims.

Referring to the drawings wherein the same part is designated by the same reference numerals wherever they occur, Figure 1 is a front view of a lay and its adjuncts embodying one form of my invention; Fig. 2 is a top plan view of the lay shown in Fig. 1; Fig. 3 is a vertical section through a well known form of loom, showing the same however as equipped with the embodiment of my invention as is shown in the preceding figures; Fig. 4 is a section through my preferred form of circuit closer, taken on line 4-4 of Fig. 5; Fig. 5 is a section taken on line 5-5 of Fig. 4, and Fig. 6 is a perspective detail view of the main shaft with the circuit closing disks thereon.

10 designates the frame work of a loom, 11 the main shaft, 12 a counter shaft geared thereto and having a crank 13. 11 designates the lay connected to the crank 13 by connecting rod 15, and on the lay is mounted the shuttle-race 16 for the shuttle 17. All these parts may be of any ordinary or desired type and form, no part of my invention.

55 Mounted at each end of the shuttle-race is a pair of solenoids 18, the solenoids of each

pair being spaced apart sufficiently to permit of the ready exit and entrance between them of the shuttle 17. The movable cores of each pair of solenoids is formed by the 60 ends of a U-shaped bar 19, each end of which is adapted to enter the pair of solenoids with the part 20 forming the base of the U in position to engage the end of a shuttle, as best shown in Fig. 2, and forms 65 the shuttle throwing elements. Each of these shuttle throwing elements is normally held in its retracted position by light coil springs 21.

In order to close the circuits through the 70 solenoids 18, without the production of any spark, as is very desirable, as sparks are very dangerous in a room where looms are working, I provide a pair of circuit closers 22, one of which is connected to one pair of 75 solenoids and the other to the other, and both preferably connected to a single battery 23, by the wire 24'. Each circuit closer 22 comprises a cup or receptacle 24 mounted on a suitable support 25, said cup 80 being adapted to contain oil or the like, as indicated in Figs. 4 and 5.

26 is a pair of contact fingers, one mounted on each side of each cup 24, and to these fingers are connected the wires 24'. 85

27-27 is a pair of disks fast on the main shaft 11, one of which is adapted to extend into each cup 24 and extend between the contact fingers 26. These disks are made of hard wood, rubber or other suitable material 90 which is a non-conductor of electricity. Into an aperture cut in the body of each disk is inserted a block 28 of brass or other suitable metal which, during the rotation of the disk, will pass between the contact fingers 26, thus 95 closing the circuit through them. By having the circuit closed in a bath of oil all danger of sparks is eliminated.

In order to prevent the oil carried up by the disk 27 from spreading along the shaft 100 11, I have provided a pair of disks 29, one located on each side of each disk 27 and spaced therefrom, the disks 29 being of such a size that they will not contact with the surface of the oil. 105

From the foregoing description of the construction of the specific embodiment of my invention which I have chosen to illustrate my invention it is believed that the operation will be apparent.

I am aware that considerable variation is possible in the details of construction herein

shown and described, without departing from the spirit of my invention, and I do not intend to limit myself thereto, except as pointed out in the following claims, in which 5 it is my intention to claim all the novelty inherent in the structure shown and described as broadly as the state of the art will permit.

Having thus described my invention what 10 I claim as new and desire to secure by Letters Patent is:

1. In a loom the combination with a lay provided with a shuttle race and shuttle, of a solenoid located at each end of the race, a 15 core for the solenoid, a part carried by the core and adapted to engage the shuttle to throw the same, and circuit closers operated by the machine independently of the shuttle for controlling the solenoids.

20 2. In a loom the combination with a lay provided with a shuttle race and shuttle, of a pair of solenoids spaced apart and located

at each end of the race, cores for each solenoid, the cores of each pair being united together to provide a means to engage the 25 shuttle to throw the same, and circuit closers operated by the machine independently of the shuttle for controlling the solenoids.

3. In a loom the combination with a lay provided with a shuttle race and shuttle, of 30 a solenoid located at each end of the race, a core for the solenoid, a part carried by the core and adapted to engage the shuttle to throw the same, and circuit closers operated by the machine independently of the shuttle 35 located in a bath whereby sparking is avoided for controlling the solenoids.

In testimony whereof I affix my signature in presence of two witnesses.

ERNEST L. DE LONG.
